UNITED STATES PATENT OFFICE.

WILLIAM S. MCLEWEE, OF TRENTON, NEW JERSEY.

DESIGN FOR A LAMP-SHADE.

SPECIFICATION forming part of Design No. 21,414, dated March 22, 1892.

Application filed February 23, 1892. Serial No. 422,587. Term of patent 7 years.

To all whom it may concern:

Be it known that I, WILLIAM S. MCLEWEE, a citizen of the United States, and a resident of Trenton, Mercer county, and State of New Jersey, have invented a new and original Design for Lamp-Shades, of which the following is a specification, reference being had to the accompanying drawings, forming a part thereof.

10 Referring to the drawings, Figure 1 represents a side view of a lamp-shade formed according to my design, and Fig. 2 a plan view.

The leading feature of my design consists in the ornamental flange or collar surrounding the opening in the top of the shade.

15 *a* is the body of the shade, and *b* the flange

or collar surrounding the opening in the top of the same. A rib *c*, having a convex surface, surrounds the flange or collar *b*, and on this rib *c* is arranged in close succession raised 20 beads or projections *d*, having a general rounded surface, as shown.

Having thus set forth my invention, what I claim, and desire to secure by Letters Patent of the United States, is—

25 The design for a lamp-shade, as herein shown and described.

WILLIAM S. MCLEWEE.

Attest:

CHAS. F. DANE,
ANNIE L. HAYES.
